UNITED STATES PATENT OFFICE.

CHARLES G. SUMMERS, JR., OF BALTIMORE, MARYLAND, ASSIGNOR TO CHAS. G. SUMMERS & CO. INC., OF BALTIMORE, MARYLAND, A CORPORATION OF WEST VIRGINIA.

SAMPLE-CAN.

1,161,012.

Specification of Letters Patent. Patented Nov. 16, 1915.

Application filed May 29, 1913. Serial No. 770,556.

To all whom it may concern:

Be it known that I, CHARLES G. SUMMERS, Jr., a citizen of the United States, residing at Baltimore, in the State of Maryland, have 5 invented certain new and useful Improvements in Sample-Cans, of which the following is a specification.

This invention relates to improvised sample cans and has for its object to provide an 10 improved sample package of canned goods such as fruits and vegetables.

The object of the invention is to provide an exterior inclosing sheet-metal can of conventional size and shape for the canned 15 goods trade—said can having a specimen of the label which the actual goods offered for sale is to bear; to also provide an opening in both the label and the can wall; to inclose in the can a transparent glass receptacle containing 20 a small sample of the goods offered for sale,—the inner receptacle preferably being much smaller than the inclosing can but larger than said opening in the can-wall and label, whereby while a full sized can 25 and label are used the quantity of food material required for a sample may be reduced to a quantity much less than the full sized can will hold.

With these and other objects in view the 30 invention is illustrated in the accompanying drawing wherein,—

Figure 1, shows the complete sample can in perspective; Fig. 2, a vertical sectional view through the same, and Fig. 3, a cross-sectional detail of the same,—the section being taken on the line 3—3 of Fig. 2.

Referring to the drawing the numeral, 1, designates a cylindric sheet-metal can body having the heads or ends, 2, and enclosed circumferentially by a label, 3. The can-body has an opening, 4, in its circumferential wall and the label has an opening, 5, which corresponds in size and shape to the opening, 4, of the can-body wall,—said 45 two openings, 4 and 5, being in register.

A jar or receptacle, 6, of glass is located in the interior of the can and is provided with a cap or closure, 7, upon the removal of which the sample material, 8, such as 50 peas, beans, corn or other vegetables or fruit may be deposited therein and afterward

closed. This jar or receptacle, 6, in size is larger than either of the openings, 4, or, 5, in can-body or label, but preferably much smaller than the interior of the can-body, 55 as clearly shown in Fig. 2, of the drawing. The jar or receptacle 6, is of semi-cylindric shape, having a curved wall 9, conforming to the curvature of the cylindric can-body wall, and a diametric flat side wall 10. 60

In order to insure that the jar or receptacle will bear close against the marginal edges of the can-body opening, a suitable filling or packing material 11, is packed in the space within the can-body and particularly against the flat side 10, of the jar. This packing material 11, serves to prevent shifting or displacement of the jar 6, in the larger can-body. 65

A packing or cushion, 12, may, and preferably is placed on the bottom of the can-body so as to form a cushion for the jar or receptacle to seat upon. 70

The top end or head, 2, of the can may be soldered in place or not as desired. 75

An improvised sample can such as herein set forth materially aids a salesman in the disposal of canned goods because it displays the article both as to full sized and external appearance and the color, etc. of its internal 80 contents thereby enabling a purchaser to form a judgment as to the commercial value and salability of the goods offered.

Having thus described my invention what I claim and desire to secure by Letters Patent is:— 85

An improvised sheet-metal sample can, having in combination a can-body provided with a closed head and bottom and said body having an opening in its circumferential 90 wall; a label around the exterior circumferential wall of the can-body which label also has an opening registering with the said can-body wall-opening; a transparent glass jar whose wall conforms in shape to the 95 shape of the sheet-metal can wall at said wall-opening and said jar being within the interior of the sheet-metal can with its glass wall exposed at said wall-opening,—said glass jar being smaller than the interior 100 space of the sheet-metal can-body but larger than said wall-opening; means within the

can-body to hold the smaller glass jar in position to form a closure for said can-body wall-opening, whereby while a full sized can and label are used yet only a very small quantity of the goods material is required for the sample.

In testimony whereof I affix my signature in presence of two witnesses.

CHARLES G. SUMMERS, JR.
